(57) **CLAIM**

The ornamental design for a portion of a shoe upper, as shown and described.

DESCRIPTION

FIG. 1 is a front perspective view of a portion of shoe upper showing my new design;

FIG. 2 is a side view thereof;

FIG. 3 is a top view thereof; and,

FIG. 4 is a front view thereof.

The uneven broken line immediately adjacent to the shaded region represents an unclaimed portion of the boundary of the design. The uneven broken line showing of the eyelet element within the shaded region is for illustrative purposes only and forms no part of the claimed design. The uneven broken line showing of the remainder of the shoe upper and sole forms no part of the claimed design.
